J. H. REEDY,
THRUST COLLAR.

APPLICATION FILED MAY 27, 1920.

1,409,576.

Patented Mar. 14, 1922.

UNITED STATES PATENT OFFICE.

JOHN H. REEDY, OF HAMILTON, OHIO.

THRUST COLLAR.

1,409,576.

Specification of Letters Patent. Patented Mar. 14, 1922.

Application filed May 27, 1920. Serial No. 384,617.

To all whom it may concern:

Be it known that I, JOHN H. REEDY, a citizen of the United States, and a resident of Hamilton, Butler County, Ohio, have invented a certain new and useful Thrust Collar, of which the following is a full, clear, and exact description, reference being had to the drawings forming part of this specification.

- 10 My invention relates to collars, particularly for use in maintaining a roll on a shaft against endwise motion. In paper mill practice, for example, the paper after it is brought over a slitter, is wound onto separate rolls, by means of contact with a rotating surface applied to the paper, the paper itself being brought over cores or the like set on a freely turning shaft that rests by gravity against the rotating surface.
- 15 In such a case there will be a number of rolls of paper wound from the several longitudinal sections of the paper coming over the slitter and any endwise shifting of the rolls of paper on the winding device will obviously result in an imperfect roll, and usually will quickly make necessary a stoppage of the machine and winder.

Collars are required for application to the paper roll shafts, in winder rolls of the above character, which can be set in place and removed with ease, and which when in place will hold the paper in fixed position against any endwise play. The use of set screws in such collars is not only likely to result in an ineffective hold, but also in considerable danger to the operator. It is practically impossible to enforce the use of short set screws on machine operators because of the difficulty of getting at them, and when long screws are in use there is always a projecting metal part revolving rapidly at a point where the operator may often be called upon to work.

It is the object of my invention to provide a self locking collar for preventing endwise thrust, which adapts itself among other things to the above noted use, and which is so constructed and designed as to take care of the work of this character.

50 I accomplish my objects by that certain construction and arrangement of parts to be hereinafter more specifically pointed out and claimed.

In the drawings,

55 Figure 1 is an end elevation of the collar

taken toward the thrust receiving end thereof.

Figure 2 is a section taken on the line 2—2 of Figure 1.

Figure 3 is a perspective view of a modified form of collar.

Figure 4 is a view partially diagrammatic of the collar in use in a paper winder.

The collar comprises three main sections, viz., a thrust receiving ring, a roller retaining bushing and a controlling ring threaded on the thrust receiving ring and adjusting the bushing with relation thereto.

The thrust receiving ring or collar 1 has a threaded portion 2 at the one end thereof, over which, in my preferred construction, is threaded the controlling ring or collar 3. The collar carries a plate or plates 4, which may be mounted on the collar 3 by screws, as at 5, and which engage a groove 6 in the bushing 7. By screwing the controlling ring up on the collar 1, the bushing may be advanced through the interior of the said collar or retracted therethrough.

Preferably three knurled rollers 8 are provided, said rollers being of very hard metal and knurled spirally so as to grasp firmly any metal part against which they are pressed. The rollers have axis pins 9, 9, which are engaged between the bushing and the thrust collar portion 1.

The bushing is cut with open slots 10 at its forward end and the metal on the outside of the bushing at the edges of the slots cut away as at 11. The slots 10 provide clearance for the rollers, and the undercut portions 11 provide an elongated pocket for the axis pins or spindles of the rollers so as to permit them to slide or roll and also to move laterally.

In addition to the cut away portions 10 and 11, the thrust collar is internally cut with three main grooves 12 which taper at the base, so as to be deepest at the rear end thereof and the shallowest at the forward or thrust receiving end.

Alongside of the grooves 12 which are of a width to receive the peripheries of the rollers, there are shallow, narrow cuts 13, made to accommodate the spindles or axis pins of the rollers.

The cuts 11 do not extend the full length of the sides of the slots 10 and thus permit only a limited movement of the spindles of the rollers, and the movement of the bushing

through the collar 1 will cause the rollers to ride along the bases of the grooves 12, said bases, as a result of their incline, acting either to force the rollers inwardly or permit them to move outwardly.

The device is assembled with the rollers set in the slots of the bushing and riding in the grooves of the thrust receiving ring. It may then be readily slipped onto the shaft, 10 with which it is to be used. As shown in Figure 4 the thrust receiving end is brought up against the core pieces 14 on the shaft 15, and the controlling ring turned on the thrust receiving portion so as to cause the bushing to force the rollers forwardly and cause them to bite into the shaft.

Due to the fact that the rollers have some play in the bushing, their spindles being free to roll a considerable distance, it may be 20 observed that when the bushing has been moved forwardly as far as it will go, the rollers will still have considerable chance of forward movement with relation to both the bushing and the thrust ring.

Accordingly the bushing may be adjusted 25 in place and held there, as by means of the threads of the controlling ring, and should there be any tendency to slip further the rollers will ride up further onto the shallowest portions of the grooves 12. This they will do because of their bite into the shaft and the movements under such circumstances of the thrust ring with relation to the shaft.

An alternative structure, which is more 35 quickly operated is shown in Figure 3 in which the controlling ring instead of being screwed onto the thrust ring, is provided with a slanting closed slot 16, which engages over a screw or other detachable headed post 40 17 mounted on the rear portion of the thrust ring. The operation of the slot over the post is the same as the operation of a thread and needs no additional description.

So far as I am aware, no one in the past 45 has provided a thrust collar device for mounting on shafts, which is adjustable to a fixed clamped position over the shaft, and has in addition a movable part which while locked in a position of shaft engagement 50 has still an additional possibility of movement in case the locked position is not adequate to withstand the thrust.

I do not wish to be limited in the scope of 55 my invention because of my description of but one main form of device, since my description and drawing are rather intended as illustrating a preferred embodiment of my invention and have been selected for purposes of easy illustration of the principles 60 thereof.

Having thus described my invention what I claim as new and desire to secure by Letters Patent, is:—

1. In a device of the character described, 65 the combination of a thrust receiving mem-

ber, to mount over a shaft, a member mounted within said thrust receiving member and adapted to retain the roller or rollers transverse the axis of the shaft, and a controlling member adjustable on the thrust receiving member and connected to the roller retaining member whereby the relative positions of the said retaining member and thrust receiving member may be controlled, said rollers being adapted to engage the shaft and one of said 75 members.

2. In a device of the character described, the combination of a thrust receiving member, to mount over a shaft, a member mounted within said thrust receiving member and adapted to retain the roller or rollers transverse the axis of the shaft, and a controlling member adjustable on the thrust receiving member and connected to the roller retaining member whereby the relative positions of the said retaining member and thrust receiving member may be controlled, said rollers having spiral grooves cut in the surface thereof and said rollers being adapted to engage the shaft and one of said members. 90

3. In a device of the character described, the combination of an outer member, a series of grasping elements, an inner member for mounting said elements so as to permit movement thereof longitudinally of the outer member, tapered means on the outer member for engaging said grasping elements, and means for locking the inner member in fixed position on the outer member, without preventing longitudinal movement of the 100 grasping members in one direction at least with relation to the outer member.

4. In a device of the character described, an outer and an inner member, means for fixedly adjusting their relative positions, 105 said outer member having grooves having slanting bases cut therein, a series of grasping elements, means for mounting them in the inner member for permitting a limited longitudinal movement of them with relation to said inner member.

5. In a device of the character described, an outer and an inner member, means for fixedly adjusting their relative positions, 110 said outer member having grooves having slanting bases cut therein, a series of grasping elements, means for mounting them in the inner member for permitting a limited longitudinal movement of them with relation to said inner member, said elements 115 comprising hard metal rollers, having knurled surfaces.

6. In a device of the character described, an outer and an inner member, means for fixedly adjusting their relative positions, 120 said outer member having grooves having slanting bases cut therein, a series of grasping elements, means for mounting them in the inner member for permitting a limited longitudinal movement of them with relation 125 to said inner member.

to said inner member, said elements comprising hard metal rollers, having knurled surfaces cut with spiral grooves.

7. In a device of the character described, 5 the combination with an outer collar and an inner bushing, external threads on the outer member, a ring threaded onto said threads and having means for engaging the bushing, open slots in the bushing having short 10 grooves on two walls of the slots, knurled

rollers having spindles to ride in the short grooves, and peripheries to have clearance in the open slots, and said outer collar having longitudinal grooves cut therein, said rollers adapted to ride in said grooves, and 15 said grooves having bases sloping inwardly toward the thrust receiving end of the outer collar.

JOHN H. REEDY.
